UNITED STATES PATENT OFFICE.

ARRON M. RODEMS, OF MILWAUKEE, WISCONSIN, ASSIGNOR TO PHOENIX LIGHT COMPANY, OF MILWAUKEE, WISCONSIN, A CORPORATION OF WISCONSIN.

DESIGN FOR A LIGHTING FIXTURE.

Application filed February 11, 1922. Serial No. 660. Term of patent 3½ years.

To all whom it may concern:

Be it known that I, ARRON M. RODEMS, a citizen of the United States, residing at Milwaukee, in the county of Milwaukee and State of Wisconsin, have invented a new, original, and ornamental Design for a Lighting Fixture, of which the following is a specification, reference being had to the accompanying drawing, forming a part thereof.

The figure is a front elevation of a lighting fixture, showing my new design.

I claim:

The ornamental design for a lighting fixture, as shown.

ARRON M. RODEMS.
